US0D1110847S

(12) **United States Design Patent** (10) **Patent No.:** **US D1,110,847 S**
(45) **Date of Patent:** **** Feb. 3, 2026**

(54) **PACKAGE**

(71) Applicant: **Colgate-Palmolive Company**, New York, NY (US)

(72) Inventors: **Yongchao Tian**, Nanjing (CN); **Xuqi Zhou**, Zhenjiang (CN)

(73) Assignee: **Colgate-Palmolive Company**, New York, NY (US)

(**) Term: **15 Years**

(21) Appl. No.: **29/969,994**

(22) Filed: **Oct. 25, 2024**

(51) LOC (15) Cl. **09-03**

(52) U.S. Cl.

USPC **D9/415**

(58) **Field of Classification Search**

(57) **CLAIM**

The ornamental design for a package, as shown and described.

DESCRIPTION

FIG. 1 is a front perspective view of a package, showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

1 Claim, 4 Drawing Sheets
